Primary Examiner — Catherine S Posthauer(74) Attorney, Agent, or Firm — K&L Gates LLP(57) CLAIM

The ornamental design for a bottle cap, as shown and described herein.

DESCRIPTION

FIG. 1 is a perspective view of a bottle cap showing our new design;

FIG. 2 is a front view thereof;

FIG. 3 is a rear view thereof;

FIG. 4 is a right-side view thereof;

FIG. 5 is a left-side view thereof;

FIG. 6 is a top plan view thereof; and,

FIG. 7 is a bottom plan view thereof.

The broken lines are shown for the purpose of illustrating environmental subject matter of an exemplary bottle and form no part of the claimed design.

1 Claim, 6 Drawing Sheets(56)
